TRUNK HUNTING FINAL SELECTOR

William W. Pharis, Rochester, N. Y., assignor to General Dynamics Corporation, Rochester, N. Y., a corporation of Delaware

Application May 3, 1956, Serial No. 582,392

8 Claims. (Cl. 179—18)

My invention relates to telephone type final selectors in general and more particularly to trunk hunting type final selectors.

In the past it has been the practice to provide step-by-step final selectors of the two-motion type which are suitable for use in private branch exchange systems. In such selectors, provision is made for extending switchthrough connections between calling and called station lines in response to the dialing of two or more digits by a calling station. Frequently included in these selectors is the provision for groups of so-called switchthrough type trunks which are accessible on the same basis as called station lines. In such selectors, an arrangement is sometimes provided for providing access to a group of cut-through type trunks in response to the dialing of a single digit by a calling subscriber.

In order to meet certain system requirements, it may be advantageous in such a selector to provide access to cut-through type trunks in response to the dialing of two digits. The problems created by the inclusion of two digit switchthrough and cut-through and also single digit cut-through type trunks within the same final selector is further complicated when the selector is arranged for restricted access to certain trunk groups from calling lines of a particular type or class.

Accordingly, it is an object of my invention to provide a new and improved final selector.

Another object of my invention is to provide a new and improved one and two digit responsive final selector.

Another object of my invention is to provide a new and improved one and two digit responsive final selector capable of trunk hunting.

Another object of my invention is to provide a new and improved one and two digit responsive final selector capable of switchthrough and cut-through type operation.

Another object of my invention is to provide a new and improved restricted service type final selector.

An object of my invention is to provide a new and improved one and two digit responsive final selector capable of switchthrough and cut-through type operation which is arranged for restricted service.

Another object of my invention is to provide a new and improved restricted service type final selector wherein restricted signals may be transmitted from a calling line circuit over a path including the talking channel of the connector.

A feature of the connector forming the preferred embodiment of my invention is the provision for one and two digit type trunk hunting followed by cut-through type operation in first and second particular levels respectively, and for two digit trunk hunting followed by switchthrough operation on other levels where the first and second levels are reserved for terminating trunks and the other levels may be used for terminating subscriber lines as well as groups of trunks.

I accomplish these and other objects by providing a telephone system of the private branch exchange type having a calling line, final selector and line finder means

2

for extending a connection from the line to the selector. The final selector has incoming and outgoing ends and includes a speech transmission channel. The incoming end of the channel to which the line is connected includes a direct current signaling circuit. The outgoing end of the selector includes a set of wipers. Certain wipers of the set are connected to the outgoing end of the channel. The set also includes a test wiper. Means such as blocking capacitors is normally effective for separating the signaling circuit from the outgoing end of the channel.

The selector includes first and second particular levels and other levels to any of which the wiper set may be advanced from its normal position in a primary motion. 15 The wiper set may then be advanced into a selected level in a secondary motion. Each level includes a plurality of sets of terminals. Each terminal set is used for terminating succeeding equipment and includes speech transmission channel terminals for engagement by the channel wipers and a test terminal for engagement by the test wiper. Provision is made for applying a busy indicating potential to the test terminal of a set when the equipment connected to that particular set is in use. All the terminal sets within the first level are in a single group. Similarly, certain successive ones of the terminal sets within the second particular level and any one of the other levels may be arranged in one or more such group per level.

Operation of the line finder means and the resulting extension of a connection to the selector seizes the selector and makes the signaling circuit operative. A first directive operation of the signaling circuit is effective for causing well known means within the selector to advance the wiper set in its primary direction in order to select one of the levels. Well known means within the selector operative in response to seizure of the selector is effective following the operation of the primary means for preparing other well known means to advance the wiper set in its secondary direction under the control of the signaling circuit. Thus, in the event that the second or one of the other levels is selected, a second operation of the signaling circuit is effective for advancing the wiper set into engagement with one of the terminal sets within the selected level. Following the conclusion of the transmission of the second signal, means within the selector is effective for releasing the preparing means. Means effective in the event that one of the other levels has been selected and operative in response to the release of said preparing means is effective for thereafter rendering busy test means and switchthrough means operative. The presence of a busy indicating potential on the test terminal of the engaged set is effective for operating the busy test means and thereby transmitting a busy indicating signal to the calling line. In the absence of such a potential the switchthrough means operates for the purpose of completing a connection including the speech transmission channel and the blocking means between the calling line and the channel terminals of the set engaged by the wiper set.

60 The selector also includes other means for operating the secondary advancing means in order to cause the advance of the wiper set from a busy terminal set to the next succeeding terminal set within a group. This other means may be controlled over any of a first, second, or third circuit, all of which are completed from busy potential on the test terminal of the set engaged by the wiper set. Thus I have provided first means effective in response to the operation of the above referred to busy test means in operated condition, the release of the preparing means, and to the selection of any one of the other levels for extending the first circuit to the test terminal of the set included in a group. The other sec-

ondary advancing means is thus intermittently operated until an idle terminal set is engaged, at which point the absence of busy indicating potential on the test terminal allows the switchthrough means to operate.

The above referred to second and third circuits are effective for energizing the other secondary advancing means and are used for controlling the cut-through means. Thus, second means is provided to be operative in response to the operation of the busy test means, the release of the preparing means, and to the selection of the second particular level for extending the second circuit to the test terminal of the wiper set and for preparing the cut-through means for operation. The other secondary advancing means is thus operated until an idle indicating potential is encountered on the test terminal of an engaged set. The second means also connects the second circuit to the prepared cut-through means, thereby making the energized second circuit effective to prevent the cut-through means from operating. The advance of the wiper set into engagement with an idle terminal set de-energizes the second circuit and consequently allows the cut-through means to operate. The operation of the cut-through means is effective for completing a metallic connection (i. e., without the blocking means) from the calling line and the channel terminals of the set engaged by the wiper set.

Third means is provided effective in response to the operation of the preparing means and to the selection of the first level for extending the third circuit to the test terminal of an engaged set and for preparing the cut-through means for operation. Means within the selector is effective for connecting busy potential to the third circuit until the wiper set has been advanced into engagement with the first terminal set in the group. Thereafter the secondary advancing means is energized over the third circuit in the manner described in the case of the second level, so that the wiper set advances until an idle terminal set is encountered. At this point the cut-through means is again operated with the previously noted effects.

Further objects and advantages of my invention will become apparent as the following description proceeds. The points of novelty which characterize my invention are set forth with particularity in the claims annexed to and forming a part of this specification. For a better understanding of the description, reference may be had to the accompanying drawings in which:

Figs. 1-3 when placed side by side in numerical order from left to right show a telephone system including: in Fig. 1, skeletonized representations of calling subscriber lines and a line finder; in Figs. 1 and 2, a final selector circuit; and in Fig. 3, skeletonized representations of the terminating circuits to which the final selector has access.

The apparatus referred to in the following description is made to function from power supplied from a first source such as a battery. The most positive terminal or plate of the battery is connected to ground and is referred to hereafter as "ground" and in the drawings as (+). The most negative, ungrounded terminal or plate of the battery is referred to as "battery" and in the drawings as (-). A second power source comprising a 20 cycle generator of the well known type in series with a ring trip battery is used for signalling. One side of the generator and ring trip battery is grounded and is hereafter referred to as "ground" and in the drawings as (+). The other, ungrounded side of the generator and ring trip battery is referred to as "generator" and in the drawings as Gen.

Extension of a connection from a calling line to the final selector

The telephone system in which the preferred embodiment of my invention is incorporated includes a plurality of subscriber lines such as 10 and 11. Each of these lines extends from a station such as A to a terminating

line circuit such as LC10 within a central office. Well known means such as a hookswitch at the station is effective for seizing the line to which it is connected in order to place a calling condition on that line. Thus, in the case of station A, the closure of hookswitch contacts H10 is effective for operating the line relay LA over the following circuit: from ground through break contacts COA1, conductor 10a, make contacts H10, break contacts D10, transmitted T10, conductor 10b, break contacts COA2, and the winding of relay LA to battery.

The operation of relay LA is effective for causing means such as an allotter (not shown because it does not form a part of the present invention) to operate and thereby cause well known means within line finder LF10 to advance the finder wiper set comprising wipers TF, RF, HSF and SF into engagement with the corresponding terminals of the calling line circuit, in this case, LC10. The operation of line finder LF10 is effective for extending a connection from the calling line 10 to the incoming end comprising conductors T1 and R1 of the final selector associated with line finder LF10. The extended connection includes an operating circuit for calling bridge relay CB. The circuit is traced from ground through break contacts PD1, the winding 1 of relay CB, break contacts AB1 and CT2, conductor T1, wiper TF, terminal T12, conductor 10a, make contacts H10, break contacts D10, transmitter T10, conductor 10b, terminal R12, wiper RF, conductor R1, break contacts CT3 and AB3, and winding 2 of relay CB to battery. Relay CB operates.

The operation of relay CB is effective to initiate the seizure of the final selector switch by causing the operation of seizure responsive means such as release delay relay RD. The circuit for operating relay RD is traced from ground through break contacts CT13, make contacts CB2, and the winding of RD to battery. Relay RD thereupon operates.

The operation of relay RD is effective at this time to pass back ground to the sleeve terminal of the calling line circuit terminal and the winding of cut-off relay within that line circuit (terminal S12 and relay COA, in the case being considered here). The circuit is traced from ground through make contacts RD1, conductor S1, wiper SF, terminal S12, make contacts LA1, and the winding of relay COA to battery. Relay COA operates at this time. The operation of relay COA is effective for removing ground from the above traced operating circuit for relay LA and disconnecting the relay winding from conductor 10b by opening break COA1 and COA2, respectively. At the same time, a locking circuit for relay COA is established between the winding of relay COA and terminal S12 through make contacts COA3 so that the subsequent release of relay LA is not effective at this time for releasing relay COA. Relay LA thereupon releases.

Returning to the consideration of the seizure of the final selector, the operation of relay RD is also effective at this time for applying ground to (energizing) master ground conductor MG associated with the final selector at make contacts RD5. The conductor MG is used as a source of ground potential within parts of the selector so long as the selector is held in seized condition by the operation of relays CB and RD. In the drawings, connections to the master ground conductor are indicated by the symbol MG.

The energization of conductor MG is also effective for completing operating circuits for primary delay relay PD and secondary delay relay SD, and pulse hunt relay PH. The circuit for operating relay PD is traced from conductor MG through primary off-normal break contacts PON19, winding 1 of relay PD to battery. The circuit for operating relay SD is traced from master ground through break contacts SON13, winding 1 of relay SD to battery. The operation of relay SD is effective for completing an operating circuit for pulse hunt relay

from conductor MG through make contacts SD3 and the winding of relay PH to battery. Relay PH operates at this time.

The operation of relay RD also prepares at make contacts RD2 a circuit for operating busy test relay BT and opens at break contacts RD6 an energizing circuit for release magnet R.

Advancing the final selector

Following the establishment of a connection from a calling line to the incoming end final selector and to the seizure of the final selector in the above described manner, the transmission of the series of signals from the station, such as A, connected to the calling line is effective for operating a signaling circuit comprising the windings of relay CB which are connected over the above-traced operating circuit to the incoming end of the final selector. The signals comprise trains of one or more impulses caused by the repeated opening of the dial break contacts D10 at calling line station A. Relay CB releases in response to each opening of contacts D10. The resulting impulsive operation of relay CB is effective for causing means including primary magnet P and secondary magnet S within the final selector to advance the wiper set comprising wipers TS, RS, SS and HSS, which are a part of the outgoing end of the final selector, in primary and secondary directions respectively. By its primary advance, the wiper set selects a level of terminal sets. The secondary direction advance is effective to place the wipers of the set in engagement with corresponding terminals in one of the sets within the selected level.

Primary movement.—Assuming that it is desired to extend a call from station A to another station such as C, signals effective for moving the wiper set in the primary and secondary directions into engagement with the terminal set associated with line circuit LC12 and line 12 are transmitted from the dial at calling station A. In response to each release of relay CB during the first impulsive operation and to the operation of relay PD, a circuit is completed for energizing the primary advancing means including magnet P. Each energization of magnet P is effective to advance the wiper set one step in its primary direction. Relay RD is a slow release type, so that the momentary opening of its operating circuit at contacts CB2 during the impulsive operation of relay CB does not release relay RD. The exact manner in which the primary advance of the wiper set is accomplished is next described. During each release of relay CB during the transmission of the first series of impulses, a circuit for energizing magnet P is completed as follows: from ground through break contacts CT13 and CB1, make contacts RD3 and PD6, and the magnet P to battery.

Also completed at the same time is an obvious holding circuit through winding 2 of relay PD which is in parallel with magnet P. The establishment of the holding circuit for relay PD, a slow release type, prevents the release of that relay during the transmission of the signal even though the above described operating circuit including winding 1 is opened at contacts PON10. An opening of the above described operating circuit for relay PD which includes winding 1 is made upon the advance of the wiper set away from its normal position by the operation of primary off-normal means including contacts PON10. Thus relay PD is held operated until the transmission of the first train of impulses has been completed; at that time relay CB comes to rest in its operated condition to open the operating circuit for magnet P and the holding circuit for relay PD at contacts CB1. Relay PD thereupon releases.

Secondary movement.—At this time the wiper set comprising wipers TS, RS, SS and HSS has been advanced to a point opposite one of the levels in which station lines, such as C, are terminated. The release of relay PD is effective for opening the above traced energizing circuit for magnet P and winding 2 of relay PD at make con-

tacts PD6 and for preparing a circuit for energizing secondary magnet S by closing contacts PD7.

Thereafter, the transmission of the second train of impulses causes a second impulsive operation of relay CB in order to transmit a series of impulses to the secondary advancing means including magnet S. The energizing circuit for magnet S is traced from ground through break contacts CT13 and CB1, make contacts RD3, break contacts PD7, make contacts SD6 and PH8 and magnet S to battery. An obvious holding circuit for relay SD is traced from the winding of magnet S through make contacts SD5 and winding 2 of relay SD to battery. Thus, relay SD is maintained in its operated condition throughout the transmission of the second train of impulses even though the above traced operating circuit comprising winding 1 of relay SD is opened. Upon the advance of the wiper set into engagement with the first set of terminals within the selected level secondary off-normal means including springs SON13 are opened to interrupt the previously traced operating circuit comprising winding 1 of relay SD. Thus, upon the completion of the transmission of the second impulse train, when relay CB comes to rest in its operated condition, the energizing circuit of magnet S and the holding circuit of relay SD are opened at break contacts CB1. Relay SD thereafter releases.

In addition to advancing the main wiper set comprising TS, RS, SS and HSS in the primary direction, the operation of the magnet P is effective for advancing level marking wipers X and XX across banks of level indicating terminals XB and XXB, respectively. The engagement by these wipers of the corresponding terminals is effective for indicating to which of the levels the main wiper set has been advanced. In the preferred embodiment of my invention, I have shown a final selector switch in which subscribers' lines are terminated in the fifth through eighth levels inclusive. Such levels are characterized by connection of the XXB bank terminal through wiper HSS by way of B wiring and contacts BT3 for purposes which are to be explained presently.

Busy test.—When the wiper set comprising TS, RS, SS and HS wipers has been advanced into engagement with any one of the terminal sets within a station line level, means comprising busy test relay BT is effective for determining whether or not the contact set so engaged is in its normal idle condition or has been made busy by other equipment in the office. A busy condition is indicated by the presence of ground on the one of the terminal sets engaged by wiper SS. The presence of battery potential on the same terminal indicates an idle condition.

Assuming for the moment that the engaged terminal set is in busy condition and consequently that a ground potential has been applied to wiper SS, a circuit for energizing relay BT is completed from wiper SS through break contacts CT7, make contacts RD2, break contacts SD1, make contacts PH6, break contacts OF10 and the winding of relay BT to battery. Relay BT thereupon operates.

Returning to the point in time at which relay SD released, upon the release of relay SD, the above traced operating circuit for relay PH is opened at make contacts SD3. Relay PH, a slow release type, is held operated for an interval of time sufficient to allow relay BT to operate over the above traced circuit. Relay PH thereafter releases to open the operating circuit of relay BT at make contacts PH6.

Following the release of relay PH, a locking circuit for relay BT is established from grounded conductor MG, through make contacts BT5, break contacts PH5 and OF10 and the winding of relay BT to battery.

The operation of relay BT is effective at this time for connecting busy tone to the calling subscriber line in order to inform the subscriber that the attempted connection cannot be made owing to the busy condition of the

called line. The tone connection is extended from a grounded, low impedance busy tone source (not shown) connected to terminal BYT through break contacts PH2, make contacts BT1, break contacts SW3, winding 1 of relay AB, capacitor C1, through the previously traced loop to calling line station A comprising conductors T1 and R1 and winding 2 of relay CB to battery and thence to ground.

Switchthrough.—In the event that the terminal set engaged by wiper SS of the terminal set engaged by the wiper set is in idle condition, the test terminal of the final selector is prepared for a switchthrough operation, i. e., a completion of the talking channel from the incoming conductors T1 and R1 through blocking means comprising capacitors C1 and C2 to the outgoing end of the selector channel comprising wipers TS and RS as well as the terminals engaged by those wipers in the manner to be set forth presently. The blocking means is effective at this time to separate the direct current signaling circuit comprising the winding of relay CB connected to the incoming end of the channel from the outgoing end of the channel comprising wipers TS and RS. Upon engagement of a set of terminals by the wiper set, the absence of ground potential on wipers SS during the time that relay PH remains operated prevents the operation of relay BT over the above described circuit. Therefore, relay BT remains unoperated and relay PH releases. A circuit is completed for operating switchthrough relay SW in response to the release of relay PH and the unoperated condition of relay BT. The circuit is traced from master ground through winding 1 of relay SW, break contacts BT6, PH7, CT10 and SD1, make contacts RD2, break contacts CT7, wiper SS, the terminal engaged wiper SS, to the resistance battery. Relay SW thereupon operates and completes a locking circuit for itself from grounded conductor MG through make contacts SW7 and winding 2 of relay SW to battery.

The operation of relay SW is effective for rendering well known means comprising ring trip relay RT effective to complete a circuit for energizing the well known alternating current signaling means at the called subscriber station such as C. This circuit is traced from the generator through winding 1 of relay RT, break contacts RT4, make contacts SW5, wiper RS, through the conductor 12b of line 12 and the bridged alternating current responsive signaling device (not shown) at station C, line conductor 12a, wiper TS, make contacts SW1 and break contacts RT1 to ground. Current from the generator flowing through the high impedance path including the station C signaling device is not sufficient to operate relay RT. When the telephone at station C is removed from its cradle, a low impedance path is completed between conductors 12a and 12b of line 12 which allows enough current to pass from the tripping battery through the above traced circuit including winding 1 of relay RT to allow relay RT to operate.

The operation of relay RT is effective for completing a locking circuit for itself from grounded conductor MG through make contacts RT11 and winding 2 of relay RT to battery.

The operation of relays SW and RT and the creation of the low impedance path between conductors 12a and 12b is effective for operating supervisory means comprising answering bridge relay AB. The operating circuit for relay AB is traced from ground through make contacts SW2, winding 1 of relay AB, make contacts RT1 and SW1, wiper TS, conductor 12a of called line 12, the low impedance path between the conductors 12a and 12b at station C, conductor 12b, wiper RS, make contacts SW5 and RT3, and winding 2 of relay AB to battery. Relay AB thereupon operates. The operation of relay AB reverses the direction of current flow through the previously traced operating loop of relay CB at reversing contacts AB1—2 and AB3—4.

The operation of relay SW and the subsequent opera-

tion of RT is also effective for completing a connection between the talking channel of the incoming end of the selector comprising conductors T1 and R1 and the talking channel of the outgoing end of the selector comprising the wipers TS and RS. One side of this circuit is traced from conductor T1, break contacts CT2, make contacts AB4, capacitor C2, make contacts RT3 and SW5 to wiper RS; the other side of the talking channel is traced from conductor R1 through break contacts CT3, make contacts AB2, capacitor C1, make contacts RT1 and SW1 to wiper TS. With the incoming and outgoing ends connected in the previously described manner to calling line 10 and called line 12, respectively, station A is connected to station C and the signaling circuit which includes the windings of relay CB is separated from the outgoing end of the final selector which includes wipers TS and RS by blocking capacitors C1 and C2.

Trunk hunting in levels.—The final selector which includes the preferred embodiment of my invention is equipped for successively advancing the wiper set comprising wipers TS, RS, SS and HSS over successive terminal sets within any one of the levels containing subscribers' lines on the previously described switchthrough basis. Within each terminal set except the last in such a group, the terminals engaged by the S and HS wipers are strapped together. Thus, in all cases except the last terminal set within such a group, a busy indicating potential extended to wiper SS is also extended to wiper HSS.

In addition to the previously described means comprising make contacts CB1 of the impulse repeating relay CB, other means comprising hunt assist relay HA is provided for operating a secondary advancing means comprising secondary magnet S20. The previously described level marking XXB terminals corresponding to the levels in which station lines are terminated are employed in the following manner for completing a first circuit for energizing relay HA.

Upon the engagement of a busy set within a group of terminals by the main wiper set comprising wipers TS, RS, SS and HSS, the above-described circuit for operating relay BT is completed in the previously described manner. During the time that relay PH is in its operated condition, a first circuit for energizing relay HA is completed from the busy indicating ground applied to wiper HSS, make contacts BT3, B wiring, the level marking XXB terminal, wiper XX, break contacts OF12 and S10, make contacts PH9, break contacts SD7 and CT15, the winding of relay HA and break contacts HA1 and R11 to battery. Relay HA thereupon operates and completes for itself a locking circuit from grounded conductor MG through make contacts HA3, break contacts S10, make contacts PH9, break contacts SD7 and CT15, the winding of relay HA and break contacts HA1 and R11 to battery. The operation of relay HA is effective for completing an energizing circuit for maintaining relay PH in its operated condition. This circuit is traced from grounded conductor MG through make contacts HA2, break contacts CT12 and SD4 and the winding of relay PH to battery.

The operation of relay HA is effective in response to the operation of relay PH for closing an energizing circuit for secondary magnet S through make contacts HA2 and PH8 and magnet S to battery. The operation of magnet S is effective at this time for advancing the wiper set out of engagement with the busy terminal set and into engagement with the succeeding terminal set within the group. The operation of magnet S is effective for opening the above-described locking circuit for relay HA at break contacts S10, so that relay HA is released.

Following the advance of the wiper set into engagement with the above referred to succeeding terminal set, the previously described busy test operation is repeated. In the event that the terminal set currently engaged is in busy condition, relay HA reoperates and thereafter magnet S is re-energized as in the previously described manner.

In the event that the terminal set is in idle condition, no ground is extended over the above-traced circuit including wiper HSS, so that the above-described operating circuit for relay HA is not completed. Relay HA fails to operate at this time, thereby opening the above-described holding circuit for relay PH at make contacts HA2 for an interval of time sufficient to release relay PH. The release of relay PH and the presence of the idle-indicating battery potential on main wiper S is effective for operating SW in the previously described manner. The operation of relay SW is effective to complete the previously described alternating signaling circuit and to prepare relay RT for operation. Thereafter the call from station A to station C proceeds in the manner previously set forth.

In the event that all the terminal sets including the last within the called group are in busy condition, the absence of a strap between the terminals engaged by the SS and HSS wipers opens the previously described operating circuit for relay HA. The failure of relay HA to operate prevents the further operation of magnet S and stops the advance of the wiper set in the secondary direction within the selected level. Thereafter relay PH releases in the previously described manner and relay BT remains in its operated condition in order to provide busy tone to the calling line.

Cut-through operation

Two digit operation.—Certain types of apparatus to which the calling subscriber line may have access by way of the selector forming the preferred embodiment of my invention may require an arrangement whereby a metallic connection is to be established between the conductors of the calling line and the conductors of the called line or trunk. Such trunks are usually arranged in groups so that it is necessary to provide means for advancing the wiper set of the final selector in its secondary direction over the busy ones of successive terminal sets within such a group. It may also be necessary to provide two digit operation, i. e., for the selection of the first trunk in such a group after the directive primary and secondary movements of the main wiper set have been made in response to the transmission of first and second directive signals to the selector.

In the final selector forming the preferred embodiment of my invention, trunks of the two digit type are terminated in the tenth level. Means for bringing about cut-through operations are also provided. In the preferred embodiment of my invention, the cut-through means are controlled by the above described level marking means. Accordingly, levels in which two digit trunks are terminated are characterized by D wiring connected to the appropriate XXB terminal for purposes to be explained presently.

After the primary direction advance of the main wiper set to the tenth level and the subsequent secondary direction advance of the wiper set within that level has taken place in response to the transmission of directive signals to the final selector, relay SD releases in the previously described manner. The release of relay SD is effective for establishing the previously traced circuit comprising make contacts PH6 for rendering relay BT operative. Thus, the presence of busy indicating ground potential on the terminal corresponding engaged by wiper SS of the engaged terminal set operates relay BT in the previously described manner.

Within the tenth level group of trunk terminal sets, the terminals engaged by main wipers SS and HSS are strapped in the previously described way that corresponding terminals in the group of station line terminal sets are strapped. Thus, upon the advance of the wiper set into engagement with a busy trunk in a group of the tenth level trunks, a second circuit for energizing relay HA is completed as follows: from ground through wiper HSS, make contacts BT4, PH3 and now operated secondary off-normal contacts SON10, break contacts CT9 and RT7,

make contacts PH4, D wiring, the tenth XXB terminal, wiper XX, break contacts OF12 and S10, make contacts PH9, break contacts SD7 and CT15, the winding of relay HA and break contacts HA1 and R11 to battery. Relay HA operates and in the previously described manner completes the locking circuit for itself at make contacts HA3 and the circuit for energizing relay PH and magnet S at make contacts HA2. Thus, relay PH is maintained operated and magnet S is operated in order to advance the wiper set into engagement with the next succeeding terminal set within the group of trunks where the busy test is repeated. The main wiper set is advanced in this manner until an idle terminal set within the group is encountered, or until all terminal sets within the group have been found busy.

The operation of the secondary off-normal springs upon the advance of the wiper set in the secondary direction is effective for removing a short around the winding of relay CT which is traced from the lower winding terminal through break contacts SON11 and CT9 at contacts SON11. The lower terminal of the relay CT winding is connected to ground through make contacts RD1 and break contacts PD4 and BT2. The engagement of a busy terminal set by the main wiper set is effective to connect ground over the above traced circuit comprising wiper HSS and make contacts BT4 to the upper winding of relay CT. The operation of relay CT is prevented at this time.

Upon the advance of the main wiper set into engagement with the terminal set of an idle trunk, ground is absent in the previously described manner from the HSS wiper, and consequently, the upper terminal of the relay CT winding. The removal of the short from around the winding of relay CT allows cut-through means comprising relay CT to operate. The circuit for operating relay CT is traced from ground through make contacts RD1, break contacts PD4 and BT2, the winding of relay CT, break contacts RT7, make contacts PH4, D wiring, the XXB terminal, wiper XX, break contacts OF12 and S10, make contacts PH9, break contacts SD7 and CT15, the winding of relay HA, and break contacts HA1 and R11 to battery. Current flowing through the windings of relays CT and HA in series is insufficient to operate relay HA, so that the latter relay remains released at this time.

The operation of relay CT is effective for establishing a locking circuit for itself from ground through make contacts RD1, break contacts PD4 and BT2, the winding of relay CT, make contacts CT14, the winding of relay HA, and break contacts HA1 and R11 to battery. Similarly, the operation of relay CT is effective for opening its above-traced operating circuit at break contacts CT15.

The operation of relay CT is effective for maintaining relay PH operated from master ground through make contacts CT11, break contacts SD4 and the winding of relay PH to battery. Relay PH is held operated in order to maintain the operating circuit of relay CT closed at make contacts PH4 until the trunk circuit terminated on the set engaged by the main wiper set has been seized.

The operation of relay CT is also effective for transferring the incoming end of the selector talking channel comprising conductors T1 and R1 from its connection to the signaling circuit comprising the windings of relay CB into a direct metallic connection with outgoing end of the selector talking channel comprising wipers TS and RS. The opening of the previously described connection between the conductors and relay CB is effected at contacts CT2 and CT3. The closing of the connection between the incoming conductors and wipers TS and RS is effected at contacts CT1 and CT4, respectively.

Referring to Fig. 3, the trunks terminated in the tenth level on which two digit cut-through service is given are of the type shown in trunk termination TT10. Upon the operation of the cut-through means comprising relay CT, a metallic connection is established between the calling line conductors and the conductors connected to the

ones of the terminal set engaged by wipers TS and RS in order to provide an operating circuit for calling bridge relay CBA in the termination. The latter circuit is traced from ground through winding 1 of relay CBA, wiper TS, make contacts CT1, conductor T1, thence over the previously traced calling line loop by way of the hookswitch contacts such as H10 at the calling station and back to conductor R1, and through make contacts CT4, wiper RS and winding 2 of relay CBA to battery. Relay CBA thereupon operates. The operation of relay CBA is effective for completing an operating seizing means within the termination circuit such as release delay relay RDA from ground through make contacts CBA1 and the winding of relay RDA to battery. The operation of relay RDA is effective for passing ground back to wiper SS in order to indicate a busy condition to final selectors other than the one shown in Fig. 2 and for supplying ground potential to conductor S1 in order to hold the calling line circuit and the final selector in seized condition.

The above-described disconnection of the windings of relay CB from the calling line conductors is effective for releasing that relay. The release of relay CB opens the operating circuit of relay RD at make contacts CB2. Relay RD thereafter releases to open the above-described operating and holding circuits for relay CT at contacts RD1. Relay CT does not release at this time because conductor S1 is grounded from the succeeding trunk termination. The release of relay RD removes ground from conductor MG in order to release relay PH.

Thereafter, the selector and trunk termination TT10 remain seized under the control of the calling line 10 and station A.

Single digit operation.—In addition to the two digit cut-through operation described above, it may be necessary to provide means effective to cause the selector to advance in its secondary direction following the transmission of a single directive signal to the selector and the resulting selection of a level and to make the selector operate on a cut-through basis. To this end, in the preferred embodiment of my invention, trunks accessible in response to the dialing of a single digit are shown terminated in the ninth level. Upon the selection of the ninth level means comprising the ninth terminal in the XB bank of terminals to which ground is connected by M wiring are effective for operating relay RT. The circuit is traced from ground through M wiring, the ninth XB terminal, wiper X, break contacts SW7 and PD5, make contacts CB3, break contacts RT10, and winding 2 of relay RT to battery. Relay RT operates and establishes an obvious locking circuit from master ground through make contacts RT11 for itself. Owing to the preliminary make nature of contacts RT11, the locking circuit is completed prior to the opening of the above traced operating circuit at break contacts RT10 so that there is no discontinuity in the operation of relay RT.

Upon the primary advance of the main wiper set comprising TS, RS, SS and HS to the level in which the single digit cut-through trunks are terminated, relay PD releases in the previously described manner. At this time, relays SD and PH are maintained at their operated condition.

The ring trip relay RT used to control signaling at the called station telephone in the previously described manner is reused at this time as means for controlling a circuit for operating relay HA. Thus, the operation of the means comprising relay RT is effective in response to the operation of relay PH for completing a circuit for operating relay HA in order to advance the wiper set comprising TS, RS, SS and HS from the point opposite the ninth level of terminal sets into engagement with the first terminal set within the single digit level. The circuit is traced from ground through make contacts RD1, break contacts PD4, BT2, SON11 and CT9, make contacts RT6, C wiring, terminal 9 in the XB

bank, the XX wiper, break contacts OF12 and S10, make contacts PH9 and RT12, break contacts CT15, the winding of relay HA and break contacts HA1 and R11 to battery. Relay HA thereupon operates.

5 The operation of relay HA is effective in the manner previously described for establishing a locking circuit for itself at break contacts HA3 and for extending an energizing circuit to secondary magnet S at make contacts HA2. Similarly, the closing of contacts HA2 is effective in the 10 previously described manner for maintaining relay PH operated; contacts HA2 are also effective at this time, owing to the operated condition of relay SD, for completing a locking circuit for relay SD through make contacts PH8 and SD5 and winding 2 of relay SD to battery.

The operation of magnet S is effective for advancing the wiper set into engagement with the first terminal set in the selected ninth level. Upon the engagement of the 15 first trunk, a test circuit is completed for determining whether or not the terminal set so engaged is in busy condition. As in the case of the above-described tenth

20 level trunks, a busy condition is indicated by the presence of a ground potential on the one of the engaged terminal sets engaged by wiper SS. The presence of busy potential on wiper SS is effective in response to the operation of 25 relays RT and SD for completing a third circuit for energizing relay HA which is traced from wiper SS through break contacts CT7, make contacts RD2 and SD2, C wiring, the ninth terminal in the XXB bank, the XX wiper, break contacts OF12 and S10, make contacts PH9 and 30 RT12, break contacts CT15, the winding of relay HA and break contacts HA1 and R11 to battery.

Prior to the secondary direction advance of the main 35 wiper set into engagement with the first terminal set in the ninth level, a circuit is completed for shorting out the winding of relay CT in order to prevent the latter relay from operating, from the lower winding terminal of relay CT through break contacts SON11 and CT9 to the upper winding terminal of relay CT. Upon the advance of the main wiper set in its secondary direction, 40 secondary off-normal means comprising break contacts SON11 are effective to open the short and to interrupt the original energizing circuit for relay HA. Thereafter, ground potential applied to the busy test circuit comprising wiper SS is effective for continuing to short out the relay CT winding. The busy test ground is extended to the upper winding terminal of relay RT over the following circuit: from wiper SS through break contacts CT7, make contacts RD2, ST2, and RT6 to the upper winding terminal of relay CT.

Upon the engagement of the idle terminal set, the shorting ground extended to the upper winding terminal of relay CT is removed. Relay CT now operates over a circuit traced from ground through make contacts RD1, break contacts PD4 and BT2, the winding of relay CT, make contacts RT6, C wiring, the ninth terminal in the 55 XXB bank, the XX wiper, break contacts OF12 and S10, make contacts PH9 and RT12, break contacts CT15, the winding of relay HA and break contacts HA1 and R11 to battery. As in the previously described case, the connection of the windings of relays CT and HA in series across battery and ground is effective for operating relay CT but not operating relay HA. In response to the 60 operation of the secondary off-normal means and the continuing released condition of relay HA, the holding circuit for relays SD and PH is opened at contacts HA2 for a time interval to allow the latter relays to release.

The operation of relay CT is effective in the previously 65 described manner for establishing a locking circuit for itself from ground through make contacts RD1, break contacts PD4 and BT2, the winding of relay CT, make contacts CT14, the winding of relay HA and break contacts HA1 and R11 to battery. The operation of relay CT is also effective for disconnecting the winding of relay CB from the incoming end of the selector talking 70 channel at contacts CT2 and CT3 and for establishing a

metallic connection from the incoming end of the selector talking channel comprising conductors T1 and R1 to wipers TS and RS at make contacts CT1 and CT4, respectively.

The operation of relay CT and the resulting establishment of a connection from the conductors of the calling line to trunk TT1 is effective for operating repeating means comprising calling bridge relay CBB within the termination over the loop comprising the conductors of the calling line circuit. The circuit for operating relay CBB is traced from ground through the windings 1 of relays CBB and SR, wiper TS, make contacts CT1 and conductor R1, thence over the previously traced circuit comprising the conductors of the calling line 10 and hookswitch contact such as H10 at the calling station and returning over conductor R1 through make contacts CT4, wiper RS, and the windings 2 of relays SR and CBB to battery.

The disconnection of the windings of relay CB from conductors T1 and R1 causes the release of relays CB and RD in the previously described manner. The release of relay RD is effective for removing ground potential from the master ground lead, thereby opening the locking circuit of relay RT, which thereupon releases. However, the operation of relay CBB is effective for completing an operating circuit for relay RDB from ground through break contacts RS1, make contacts CBB3, and the winding of relay RDB to battery. Relay RDB operates to pass ground back through the previously traced operating circuit including wiper SS for holding operated relay CT in the selector circuit.

Service restriction.—The selector forming the preferred embodiment of my invention is effective for extending connections from all the subscriber lines in the system to any one of the subscriber lines or trunk circuits in the manner set forth in the foregoing description. However, the subscriber lines in the contemplated system are divided into restricted and unrestricted classes. Thus, line 10 terminating in circuit LC10 is an example of a line to which unrestricted service is to be given.

Service restrictions are imposed in the preferred embodiment of my invention only in the case of connections extended over the trunks terminated in circuits such as TT11. Such trunks are shown terminated in the ninth level which is accessible in response to the dialing of a single digit into the selector. However, it is to be understood that such service restrictions might also be provided on trunks or lines terminated in other levels where those trunks or lines are accessible in response to the dialing of two directive signals into the selector and the digits are effective for causing the main wiper set to be advanced in primary and secondary directions into engagement with a particular terminal set. Referring to selector operation on a single digit basis, terminations such as TT11 include means comprising the calling bridge relay for repeating directive signals originating at the calling line station to the trunk line such as T11 extending to a distant office. The service restriction in the preferred embodiment of my invention is the preventing of the extension of connections from lines of the restricted class only to certain destinations such as toll operator positions, where the particular destination is reached by transmitting particular codes of signals as a first digit 0.

The seizure of a trunk in the ninth level is effected in the previously described manner by operating relay CBB over a loop circuit including the windings of relay CBB, the talking channel conductors of the final selector, the calling line, and the calling line station. As previously pointed out, the operation of relay CBB is effective for operating release delay relay RDB from ground through break contacts RS1, make contacts CBB3, and the winding of relay RDB to battery.

The operation of relays CBB and RDB is effective for starting the seizure process of trunk T11 to the distant office by completing an operating circuit for shunt relay SH from ground through break contacts SWB6, make con-

tacts RDB1 and the winding of relay SH to battery. Relay SH thereupon operates.

The operation of relay RDB is effective for operating release delay repeater relay RDP at make contacts RDB2. Relay RDP thereupon operates. The operation of relay RDB is effective for operating off-normal relay ON. The circuit is traced from ground through make contacts RDB2, break contacts MON and the winding of relay ON to battery.

10 The operation of relays SH, RBD, and CBB is effective for seizing trunk T11 by completing an incoming signal circuit to the distant office. The latter circuit is also effective for operating signal relay SG and is traced from ground through make contacts SH1, the winding of relay SG, make contacts CBB1 and RDB4, conductor T11b of trunk T11 through seizure responsive means at the distant office, thereby seizing distant office equipment. The seizure of the distant office equipment is effective for placing ground potential on the trunk conductor T11a in order to complete an operating circuit for switch-through relay SWB. The circuit is traced from ground through the distant office equipment, conductor T11a, make contacts RDB5, break contacts SWB3, and the winding of relay SWB to battery. Relay SWB thereupon operates.

20 The operation of relay SWB is effective for transferring the winding of relay SG from its previously described connection to ground through make contacts SH1 to conductor T11a and the distant office ground source at break contacts SWB2 and make contacts SWB1. Owing to the

30 make before break nature of contacts SWB1 and SWB2, this transfer is effected without releasing relay SG. The operation of relay SWB is also effective for disconnecting its own winding through the previously described operating circuit at break contacts SWB3 and connecting its winding to a holding circuit from ground through make contacts SG1 and SWB4 and the winding of relay SWB to battery. The operation of relay SWB is also effective for opening the operating circuit of relay SH at break contacts SWB6 and for applying ground to the wiper SS of the final selector at make contacts SWB5.

35 Returning to the circuit for operating relay CB, it is pointed out that the latter circuit includes the windings of service restricting relay SR. The relay SR windings are of equal inductance and are wired into the circuit differentially so that equal and opposite fields induced in the frame of the relay by current flowing in the group comprising the subscriber's line do not operate relay SR. Following the seizure of termination TT11, the operation of relay RDP is effective for shorting out the windings of relay SR at make contacts RDP2 and RDP3. Therefore, if relay SR is to be operated, the conditions for operating it must occur after the circuit for operating relay CB has been completed but before the operation of relay RDP.

40 Assuming that termination TT11 has been seized from a calling line of the unrestricted class, upon the transmission of a signal from the calling station dial in the previously described manner to the signal repeating means comprising relay CBB, relay CBB repeats impulses over the loop of trunk T11 comprising conductor T11a, make contacts SWB1, the winding of relay SG, make contacts CBB1 and RDB4 and conductor T11b by repeatedly opening and reclosing make contacts CBB1. In this manner, the repeating means is effective for repeating an indefinite number of directive signals of any value to the distant office.

45 In the case of calls extended from lines of the restricted class to the termination TT11, it is necessary to momentarily unbalance the loop of the operating circuit for relay CBB in order to indicate to termination TT11 that the call is extended from a restricted service line. The unbalancing of the loop of relay CBB is accomplished by connecting ground to that part of the loop associated with the upper winding of relay CBB and is effective to

make unequal current flow through windings 1 and 2 of relay SR prior to the operation of relay RDP. The method by which the unbalance of the loop is accomplished is next described.

Returning to the consideration of the line circuits and the final selector, lines of the restricted type or class are terminated in line circuits such as LC10 to wherein a ground connection is extended to the finder bank terminal HS12. The corresponding terminal, HS11, in the terminating circuits of each unrestricted type line is left ungrounded as shown in the case of line circuit LC11. When a call has been extended from a restricted type line such as L10 through line finder LF10 into the final selector, ground from the restricting terminal HS12 is extended through wiper HSF to conductor HS1. Following the operation of relay CT and the release of relay RT but prior to the release of relay PH, means comprising a circuit for unbalancing the previously described operating loop of relay CBB is actuated in order to operate the service restricting means comprising relay SR within termination TT1. This circuit is completed upon the advance of the main wiper set of the selector to the terminal set to which trunk termination TT11 is connected (i. e., before slow operate type relay RPD has had time to operate). The unbalancing circuit is traced from ground through terminal HS12, wiper HSF, conductor HS1, make contacts CT17 and PH1, break contacts RT5, wiper TS, the windings 1 of relays SR and CBB to ground. The shorting out of the upper windings of relays SR and CBB is effective in the previously described manner to allow current to flow in only winding 2 of relay SR so that the latter relay operates at this time.

The operation of relay SR is effective for completing an operating circuit for service restricting repeater relay SRP from ground through make contacts RDB3 and SR1 and the winding of relay SRP to battery. Relay SRP thereupon operates and locks itself up through an obvious circuit including make contacts SRP1.

The operation of relay SRP is effective for rendering digit counting means comprising a minor switch effective. Thus, upon each release of relay CBB during the repeating operation, a circuit for energizing the stepping magnet MX of the minor switch is completed from ground through break contacts RSI and CBB2 and make contacts RDB1 and SRP2 and the winding of magnet MX to battery. The impulsing of magnet MX is effective in the well known manner to drive minor switch wiper MW from its normal position into engagement with the one of the minor switch bank terminals corresponding to the number of impulses in the repeated train as indicated by the number of operations of magnet MX.

The advance of the minor switch wiper away from its normal position is effective for opening the above described operating circuit for relay ON at break contacts MON. Thereafter, during the repetition of impulses (i. e., when relay SH3 is operated in response to the impulsing operation of relay CBB), relay ON is maintained in its operated condition from ground supplied through make contacts RDB2, SH3 and ON1. Upon the stopping of the repeating operation of relay CBB, relay SH is released in the previously described manner to open the holding circuit of relay ON at make contacts SH3. Relay ON2 thereupon releases.

In the event that the directive signal has been transmitted from the restricted class calling line, which is effective for directing the central office equipment to a forbidden destination, minor switch wiper MW is advanced to a bank terminal connected to the winding of restricted service relay RS. The minor switch is effective under these conditions for completing an operating circuit for relay RS which is traced as follows: from ground through make contacts RDB2, break contacts ON2, shorting bar MSB, wiper MW, and the winding of relay RS to battery. Relay RS thereupon operates.

The operation of restricting relay RS is effective for

opening the previously traced operating circuit for relay RDB at break contacts RS1. Relay RDB therefore releases at this time.

The release of relay RDB is effective for opening the previously traced loop to the distant office for operating signal relay SG at make contacts RDB4. Relay SG thereupon releases, opening the operating circuit of relay SWB at make contacts SG1. Relay SWB releases.

The release of relays SWB and RDB is effective for removing ground from the operating circuit of relay SRP and the wiper SS of the previously described final selector switch. Relay SRP thereupon releases. In response to the removal of ground from wiper SS, the final selector switch is released in a manner to be described.

15 *Release of the selector*

Upon the completion of a call, either to a station line or to a trunk, the release of the final selector switch is brought about by the release of the connection under the control of the calling subscriber. In the case of a call extended to a station line wherein relay CB within the final selector is held throughout the call under the control of the calling subscriber station, return of the calling station telephone to its hookswitch and the consequent opening of the hookswitch contacts, such as H10, is effective for releasing relay CB, thereby opening at make contacts CB2 the previously described operating circuit for relay RD. Relay RD releases at this point to remove ground potential from grounded conductor MG at make contacts RD5. The removal of master ground is effective for opening the operating circuits for relays SW, RT as well as relays PD, SD, and PH if the latter are still operated.

The release of relays RD and SW is effective at this time for completing an operating circuit for release magnet R. The circuit is traced from ground through break contacts SW8, RD6 and CT16 and either of operated off-normal springs PON11 or SON12 and the winding of magnet R to battery. The operation of magnet R is effective in the well known manner for restoring the wiper set comprising TS, RS, SS and HSS, thereby opening the connection between the calling subscriber line and a called subscriber, and for restoring auxiliary level marking wiper AW to their normal positions. Other means (not shown) restore the line finder wiper set comprising wipers TF, RF, SF, and HSF to its normal position in order to disconnect the calling line from the incoming end of the final selector.

In the case of calls extended to one of the cut-through type trunks, it is to be recalled that only relay CT remains in its operated condition after the connection has been established and that the locking circuit for relay CT includes a ground connection from the succeeding equipment such as trunk termination TT10 extended over main wiper S. The restoration of the telephone at the calling station such as A to its hookswitch is effective for opening the operating circuit of the trunk circuit calling bridge relay such as CBB, the equipment succeeding the final selector. The release of the calling bridge relay releases the associated release delay relay such as RDB in order to remove ground from the wiper SS of the final selector at contacts such as RDB3. Relay CT within the final selector thereupon releases.

The release of relay CT is effective at this time for energizing the release magnet R by completing the above traced operating circuit for magnet R at break contacts CT16. The operation of relay R is effective in the previously described manner to restore the wiper set and auxiliary wiper AW to their normal positions and thereby interrupt the connection extended between the calling line and the succeeding trunk termination. Similarly, the line finder LF10 is released to disconnect the calling line from the final selector.

While I have shown and described a particular embodiment of my invention, it will be obvious to those skilled

in the art that changes and modifications may be made without departing from my invention in its broader aspects. I, therefore, aim in the appended claims to cover all such changes and modifications as fall within the true spirit and scope of my invention.

What is claimed is:

1. In a telephone system including a calling line, a selector including a set of wipers, and means for extending a connection from said line to said selector and seizing said selector, wherein said selector includes a plurality of terminal sets arranged in a plurality of levels including a particular level, means connected to each of said terminal sets for changing the connected terminal set from its normal idle condition to a busy condition, means operative in response to the transmission of a first directive signal to said selector for advancing said wiper set in a primary direction to select any one of said levels, means to be energized for advancing said wiper set in a secondary direction into engagement with any one of said terminal sets in a selected one of said levels, a circuit for energizing said secondary advancing means, means operative in response to the seizure of said selector for preparing said energizing circuit, means operative in response to the transmission of a second directive signal to said selector and to the operation of said preparing means for completing said energizing circuit in order to advance said wiper's set into engagement with a particular one of said terminal sets, and means for releasing said preparing means at the conclusion of the secondary advance of said wiper set, the combination comprising: other means for completing said energizing circuit, busy test means operative in response to the release of said preparing means and to the selection of an indicated busy one of said terminal sets for completing an operating circuit for said other means, and means operative in response to the selection of said particular level together with the operation of said preparing means and the engagement of a busy one of said terminal sets for preparing another operating circuit for said other means, whereby said secondary advancing means is prepared for operation at the conclusion of a directive primary movement of said wiper set to said particular level and may be further advanced at the conclusion of directive primary and secondary movements of said wiper set to a set of busy terminals within one of the other of said levels.

2. The telephone system set forth in claim 1 and having in addition off-normal means having an operated condition in response to the advance of said wiper set in its secondary direction, and means operative in response to the unoperated condition of said off-normal means and to the selection of said particular level for completing still another circuit for said other means, whereby said wiper set is advanced into engagement with the first of said terminal sets within said particular level at the conclusion of a primary movement of said wiper set to said first level.

3. In a telephone system including a calling line, a selector including a speech transmission channel and a set of wipers, and means for extending a connection from said line to said selector and for seizing said selector, wherein said channel includes an incoming end connected to said line by said connection extending means and an outgoing end comprising certain ones of said set of wipers, a signaling circuit, cut-through means normally effective for connecting said incoming channel end to said signaling circuit, blocking means normally effective for separating said signaling circuit from said outgoing channel end, switchthrough means for completing a connection from said incoming end to said outgoing end through said blocking means, said cut-through means being operative for completing a metallic connection between said calling line and said outgoing end, a plurality of terminal sets arranged in a particular first, a particular second, and other levels, said terminal sets in said first level and certain consecutive ones of said terminal sets in said second and said other levels being arranged in groups, means con-

nected to each of said terminal sets operative for changing the connected terminal set from its normal, idle condition to a busy condition, means operative in response to a first directive operation of said signaling circuit for advancing said wiper set in a primary direction to select any one of said levels, means for advancing said wiper set in a secondary direction into engagement with any one of said terminal sets in a selected level, a circuit for energizing said secondary advancing means, means operative in response to the seizure of said selector for preparing said secondary advancing circuit, and means operative in response to a second directive operation of said signaling circuit and the operation of said preparing means for completing said secondary advancing circuit in order to cause said wipers to engage a particular one of said terminal sets within a selected level, and means operative in response to the secondary advance of said wipers for releasing said preparing means at the conclusion of a secondary advance of said wiper set, the combination comprising: other means for completing said energizing circuit, busy test means operative in response to the selection of a busy one of said terminal sets and to the release of said preparing means, means operative in response to the operation of said busy test means and to the selection of one of said other levels for completing a first operating circuit for said other means, means normally operative in response to the unoperated condition of said preparing means and the release of said busy test means for completing an operating circuit for said switchthrough means, means operative in response to the selection of said second level for preparing a first operating circuit for said cut-through means, said second level selection responsive means being operative in response to the operation of said busy test means for completing a second operating circuit for said other means effective in the presence of a busy condition on the terminal set engaged by said wiper set for preventing the operation of said cut-through means, means operative in response to the selection of said first level for preparing a second operating circuit for said cut-through means, off-normal means having a normal condition operative in response to the advance of said wiper set in its secondary direction, said first level selection responsive means being operative in response to the normal condition of said off-normal means for operating said other means to advance said wiper set into engagement with said first terminal set within said first level, said second level selection responsive means being thereafter operative in response to the operation of said preparing means and to the engagement of a busy one of said terminal sets for completing a third operating circuit for said other means, the energization of said third operating circuit being effective for preventing the operation of said cut-through means.

4. In a telephone system comprising a line, means connected to said line for seizing and thereafter transmitting directive signals over said line, a trunk, a circuit comprising repeating means and seizure responsive means for terminating said trunk, said repeating means being effective for operating said seizure responsive means and being thereafter operative for seizing and repeating directive signals to said trunk, a selector having a normal condition and operative in response to signals transmitted from said line for selecting said trunk, means in said selector having a normal condition operative in response to the selection of said trunk for connecting said repeating means to said line in order to render said repeating means operative in response to signals transmitted over said line, said seizure responsive means being effective for thereafter maintaining said selector connecting means in operated condition, means in said selector thereafter operative in response to the operated condition of said selector and the normal condition of said connecting means for restoring said selector to normal condition, the combination comprising: means operative to any one of a plurality of unique conditions for registering the value of a

directive signal, said repeating means being operative for operating said signal registering means to one of its unique conditions corresponding to the value of a signal repeated to said trunk, and means responsive to a particular operated condition of said repeating means for restoring said seizure responsive means to normal condition, whereby said selector connecting means and said selector are restored to their normal conditions and said trunk is released following the transmission of a particular directive signal over said trunk.

5. In a telephone system comprising a first line terminating in a line circuit of a first class, a second line terminating in a line circuit of a second class, means individual to each of said line circuits for seizing and thereafter transmitting directive signals over the corresponding one of said lines, a trunk, a circuit comprising repeating means and seizure responsive means for terminating said trunk, said repeating means being effective for operating said seizure responsive means and thereafter operative for seizing and repeating directive signals to said trunk, a selector having a normal condition operative in response to the seizure of and the subsequent transmission of directive signals from either of said lines for extending a connection from the seized one of said lines to said trunk, means in said selector having a normal condition and operative in response to the selection of said trunk for connecting the seized one of said lines to said repeating means in order to render said repeating means operative in response to signals transmitted from the seized one of said lines, said seizure responsive means being effective thereafter for maintaining said selector connecting means in operated condition, and means in said selector subsequently operative in response to the operation of said selector and to the normal condition of said selector connecting means for restoring said selector to normal condition, the combination comprising: means in said termination having a plurality of operated conditions for registering the value of a directive signal, means operative in response to the extension of a connection from said first line to said trunk terminating circuit only for rendering said repeating means operative to advance said registering means to the one of said operated conditions corresponding to the value of a signal repeated to said trunk, and means responsive to a particular operated condition of said repeating means for restoring said seizure responsive means to normal condition, whereby said connecting means and said selector are restored to normal condition and said trunk is released following the transmission of a particular directive signal from said first line over said trunk.

6. In a telephone system comprising a first line terminating in a line circuit of the first class, a second line terminating in a line circuit of the second class, means individual to each of said lines receiving and thereafter transmitting directive signals over the corresponding one of said lines, a trunk, a circuit comprising repeating means and seizure responsive means for terminating said trunk, said repeating means being effective for operating said seizure responsive means and thereafter operative for seizing and repeating directive signals to said trunk, a selector having a normal condition comprising a talking

channel and a class of service conductor, means operative in response to the seizure of either of said lines for connecting the seized one of said lines to said channel in order to seize said selector and for connecting the one of said line circuits terminating the seized one of said lines to said class of service conductor, means individual to said first class of line circuit for energizing said class of service conductor, means for causing said selector to advance to said trunk termination, means in said selector having a normal condition operative in response to the seizure of said selector for rendering said advancing means operative, other means having a normal condition operative in response to the selection of said trunk termination and to the operation of said seizure responsive means for further extending a connection from said channel to said repeating means in order to render said repeating means operative in response to signals transmitted from the seized one of said lines to said trunk termination, means operative upon the advance of said selector to said trunk termination for restoring said selector seizure responsive means to normal condition, and means operative in response to the advance of said selector and the normal condition of said selector connecting means for restoring said selector to normal condition, the combination comprising: means in said termination having a plurality of operated conditions for registering the value of a signal repeated over said trunk, a circuit completed in response to the operation of said other means and said selector seizure responsive means for connecting said class of service conductor to said channel, and means operative to a particular operated condition of said repeating means for restoring said trunk circuit seizure responsive means to normal condition, and means connected to said repeating means operative in response to the completion of said connection for rendering said registering means operative.

40 7. The system set forth in claim 6 wherein said line includes first and second conductors, said repeating means includes a relay having first and second windings in series with said conductors, and said means connected to said repeating means includes a relay having first and second windings differentially connected in series with said conductors, whereby the completion of said circuit is effective for unbalancing the flow of current through said first and second windings of said differentially wired relay in order to cause said differentially wired relay to operate.

45 8. The system set forth in claim 6 wherein said termination includes means operative following the operation of said termination seizure responsive means for rendering said means connected to said repeating means inoperative, and means for maintaining said registering means operative until a first operation of said repeating means is completed, whereby said registering means is effective for registering the value of a first signal transmitted to said trunk.
